UNITED STATES PATENT OFFICE.

FRANK W. SCHWINN, OF CHICAGO, ILLINOIS.

REFRIGERATING SYSTEM.

Application filed November 16, 1925. Serial No. 69,344.

This invention relates to improvements in refrigerating systems and more especially to a system of that kind having two or more cooling compartments.

5 Among the features of my invention, is the provision of means whereby a plurality of cooling compartments may be taken care of by one compressor; even though different temperatures may be required in the separate compartments.

10 My invention will be found especially useful in all cases where there is a plurality of cooling compartments operating under different conditions. In such cases, by the use 15 of my invention, the different compartments may be handled by one compressor. For example, at soda fountains where ice cream and syrups are kept in cooling compartments, it frequently happens that it is desirable to keep the different compartments 20 at different temperatures. This may be easily done by the use of my invention.

Other features and advantages of my invention will appear more fully as I proceed 25 with my specification.

In that form of device embodying the features of my invention, shown in the accompanying drawings, Figure 1 is a view in side elevation, partly diagrammatic, showing the 30 complete apparatus; and Fig. 2 is a vertical sectional view showing one of the expansion valves and thermostatic switch.

In general, it may be stated in apparatus 35 of this kind, the refrigerating liquid passes from the pump or compressor to an expansion valve, thence to the cooling coil in the cooling compartment and back again to the compressor.

40 In the practice of my invention, a separate expansion valve is provided for each cooling compartment, and such expansion valve in turn is controlled by a thermostatic switch operated by changes in temperature in the particular compartment. When the 45 temperature in a certain compartment rises to a given point, the thermostatic means operates to open the expansion valve and permit the flow of the refrigerant. Upon the temperature dropping to a desired point, such flow is automatically shut off in order 50 to prevent the compartment from becoming too cool. Each compartment, having its own expansion valve and thermostatic switch, operates independently of the others; 55 and each switch may be set as desired in

order to give the required temperature in the compartment controlled thereby.

Each of the thermostatic devices also controls an electric switch so that when all of the expansion valves for all of the compartments are closed, the electric motor operating the compressor will be shut off. As long as any one compartment requires refrigerant, however, the operation of the compressor will continue.

60 As shown in the drawings, 10 indicates a pump or compressor operated by an electric motor 11. 12 indicates a suitable source of current supply. The particular construction and operation of the pump or compressor, 70 and the electric motor, form no part of the present invention and, consequently, the same are not shown in detail.

13 and 13^a indicate separate cooling compartments here shown as two in number. It 75 is to be understood that there may be as many of these cooling compartments as desired. Each of the cooling compartments is supplied with a cooling coil indicated by 14 and 14^a respectively.

14 represents the feed pipe carrying the refrigerant fluid from the compressor to the cooling coils and 16 indicates the return pipe from the coils to the compressor. These parts are also of well-known construction 80 and are not shown in detail.

15 represents the feed pipe carrying the refrigerant fluid from the compressor to the cooling coils and 16 indicates the return pipe from the coils to the compressor. These parts are also of well-known construction 85 and are not shown in detail.

In connection with each of the cooling coils there is also provided a thermostatically operated expansion valve and electric switch. In Fig. 1, these devices are indicated in general by 17 and 17^a respectively. One of these devices is shown more in detail in Fig. 2.

90 As shown in Fig. 2, the expansion valve comprises a casting 18 having an inlet opening 19 at the bottom to which the pipe 15 is joined. 20 indicates a removable seat threaded into the upper end of the inlet opening 19. Lying on the valve seat 20 is a valve head 21 adapted to close the orifice 22 100 therein.

95 Arranged above the valve head 21 is a diaphragm 23 and lying above this is an arm 24 pivoted at 25 at one side of the diaphragm and extending diametrically across 105 the same. The center part of the arm 24 is bent downwardly as indicated by 24^a to lie close to the diaphragm 23. The free end of the arm 24 as indicated by 24^b is provided with an adjusting screw 26, the lower 110

end of which rests on the upper end 27 of a rod carried by a sylphon or temperature responsive element 28 of any desired construction.

The portion of the rod 27 intermediate its ends is threaded as indicated by 28 and carries thereon a nut 29 provided with an annular shoulder 30.

31 indicates a swinging arm pivoted at 32, 10 carrying at its lower end a glass tube 33 having therein at one end the two electrical terminals 34, 34. Within the tube 33 is a drop of mercury 35.

The upper end of the arm 31 near the 15 pivot 32 carries a short nose 36 lying adjacent the shoulder 30 on the nut 29. A spring 37 is adapted to yieldingly hold the lower end of the arm to the left (as viewed in Fig. 2). The two electrical terminals 34, 20 34 are connected to the two wires 38 and 39 which form a part of the circuit 12 controlling the motor 11.

The construction and operation of the mechanism 17^a is the same as that of the one 25 just described. 39^a and 38^a indicate the two wires leading from the electrical switch on this device. 15^a indicates the pipe carrying the refrigerant from the compressor and 16^a indicates the return pipe from the coil. It 30 will be noticed that both electrical switches are connected with the circuit 12 controlling the electric motor 11 so that if either of the electrical switches be closed, the motor will operate; but that if both be opened, the motor will stop.

40 indicates a tube connected with the sylphon 28 and provided with a bulb 41 lying in the cooling compartment 14.

In the operation of the device, the nut 29 40 is adjusted on the threaded part 28 of the rod 27 so that the shoulder 30 will engage the nose 36 on the arm 31 and rock the same to cause the mercury 35 to flow toward the contacts 34, 34 and close the switch when the 45 temperature in the compartment 14 rises to a certain point. The action is caused by the expansion of the fluid used in the sylphon which fluid also fills the pipe 40 and the bulb 41 lying in the cooling compartment. 50 When the temperature rises to a given point this fluid expands causing the sylphon 28 to expand thus raising the shoulder 30.

The adjusting screw 26 on the arm 24 is 55 also so adjusted that at substantially the same time, the upward movement of the part 27 carried by the sylphon will raise the central portion 24^a of the arm 24 resting on the diaphragm 23 and permit the valve head 21 to rise and the expansion valve to open. 60 The arm 24 is yieldingly pressed downwardly by a spiral spring 45 as shown.

It will be seen that each of the cooling compartments is substantially controlled. When the temperature in either one reaches 65 a predetermined point the corresponding

sylphon will close the electric switch and open the expansion valve for that compartment as above described. The compressor will thereupon be started (unless it is already running) and the flow of refrigerant 70 through the cooling coil in that compartment will be permitted until the temperature drops to a certain point. Upon the temperature falling to a predetermined point, the sylphon will contract, to close the 75 expansion valve and open the electric switch. It will be noted, however, that both electric switches must be open in order to stop operation of the compressor.

The spring 45 which presses down the 80 arm 24 is held at its upper end by a rigidly mounted member 50 which has threaded in it a screw 51, the lower end of which, as indicated by 51^a extends through a hole in the arm and acts as a stop for the diaphragm 85 23. The screw 51 can be adjusted upwardly or downwardly in the member 50 in order to vary the position of such stop, and consequently vary the maximum opening of the expansion valve. 52 indicates a lock nut to 90 hold the screw 51 in its adjusted position. 53 indicates diagrammatically a condenser between the compressor and the expansion valves.

While I have shown and described certain 95 embodiments of my invention, it is to be understood that it is capable of many modifications. Changes, therefore, in the construction and arrangement may be made without 100 departing from the spirit and scope of the invention as disclosed in the appended claim, in which it is my intention to claim all novelty inherent in my invention as broadly as possible in view of the prior art. 105

What I claim as new, and desire to secure by Letters Patent, is:

In a refrigerating system; a plurality of cooling compartments; a compressor; a condenser; a cooling coil in each compartment; 110 connections between each cooling coil and the condenser; an expansion valve in connection with each cooling coil adapted to control the flow of refrigerant from the condenser to the cooling coil; thermostatically controlled means in connection with each expansion valve adapted to regulate the opening of said expansion valve in accordance with changes in temperature in the corresponding cooling compartment; an electrical 115 switch operated by each of said thermostatically controlled means adapted to be opened upon the expansion valve being closed and vice versa; a motor for driving the compressor; and electrical connections between said switch and the motor whereby said compressor will be stopped when all of said switches are open.

In testimony whereof, I have hereunto set my hand this 14 day of Nov. 1925.

FRANK W. SCHWINN.
